THREAD PULLING TOOL

Edna M. Franklin, Oklahoma City, Okla.

Application July 27, 1955, Serial No. 524,681

4 Claims. (Cl. 223—1)

The present invention relates generally to the dress-making or tailoring art, and more particularly to a unitary device for cutting fabric and threads and by which seam threads may be manually withdrawn from the goods.

The present invention is an improvement of a Patent No. 2,504,676 granted to me by the United States Patent Office on April 18, 1950.

None of the devices as shown in the prior art, nor all of them combined, with which I am familiar, which are intended for use in withdrawing seam threads from fabrics, make any provision for a cutting operation to be performed while ripping out and removing unwanted threads, and none suggest the possibility of its being so done. Since most of the thread pulling implements are formed with blunt non-cutting edges the seamstress must lay the thread pulling tool aside and obtain a pair of scissors when necessary and adapt her hands to them for use, and again reverse this procedure to get back to the thread pulling. While this seems a simple operation it is, at least, inconvenient and sometimes time consuming, particularly when the scissors may have been mislaid or may be temporarily hidden from view by the folds of the goods being worked on.

It is therefore the principal object of this invention to provide a single hand tool which may be used as a pair of scissors and also simultaneously as a thread pulling tool.

Other important objects are to provide a hand tool of this class which is easy to use, simple in its operation, and positive in its cutting and thread gripping and thread pulling function.

Another object is to provide a tool for these purposes which may be manufactured at a cost considerably less than the combined cost of the two implements now used to perform the same functions.

Further objects are to provide a tool which is small, light in weight and which has few moving parts to become worn or to get out of order.

The present invention accomplishes these and other objects by providing a hand tool having a pair of elongated members pivotally connected intermediate their ends in sliding over-lapping relation to each other and having cooperating handles at one end of the members. The body members, respectively, integrally carry two elongated blade members opposite the handles, each having a sharpened cooperating shearing edge intermediate their ends and ending in a blunt edged non-cutting tip portion. One of the tip portions has a sharpened point. A boss projects outwardly from the surface of the blade adjacent the sharpened point. The surface of the boss is provided with a recess for nesting the ball of the operator's thumb therein. The tip portion of the other blade has a blunt and extending beyond the sharpened point of the first mentioned blade.

Other objects will be apparent from the following description when taken in conjunction with the accompanying single sheet of drawings wherein:

Figure 1 is a perspective view of the device with its

2

blades in closed position, the dotted lines illustrating the open position of the blades, and also depicting, in dotted lines, a thread engaged by the non-cutting tips of the two blades;

5 Figure 2 is a fragmentary elevational edge view of the tool with the blades in closed position;

Figure 3 is a fragmentary top view of the non-cutting tip portions of the blades; and

Figures 4 and 5 are transverse vertical sectional views 10 taken substantially along the lines 4—4 and 5—5, respectively, of Fig. 1.

Like characters of reference designate like parts in those figures of the drawings in which they occur.

In the drawings:

Referring to Fig. 1 the reference character A indicates, as a whole, an elongated element which constitutes the bottom body member of the device. The bottom member A has a comparatively small rod-like handle portion 6 formed into a looped handle or finger grip 8 at its rear end. The forward end of the handle portion 6 is substantially rectangular in cross-sectional area and ends in a rearwardly facing abrupt vertical shoulder 10, and therebeyond, in a forwardly direction, there extends a thinner, vertically tapered blade portion 12, the side edges of which also taper in a forward direction. The extreme forward end of the blade portion terminates in a rounded or blunt tip 14. The upper surface of the blade portion 12 is transversely flat and has a left hand vertical sharpened shearing edge 16, viewed from the rear, terminating 30 forwardly in a dull non-cutting edge 18 (Fig. 3) adjacent the point 14. Longitudinally the blade 12 is arcuately curved downwardly as is illustrated best in Fig. 2.

The reference character B indicates, as a whole, an elongated element which constitutes the top body member 35 of the device. The top member B also has a comparatively small rod-like handle portion 20 which is similar to the handle portion 6 of the member A, and which is formed rearwardly into a looped handle or finger grip 22 in co-operation with the handle grip 8. The forward end 40 of the handle portion 20 is similarly rectangular in cross-sectional area and terminates in an abrupt vertical shoulder complementary with the shoulder 10 of the member A.

The top member B has a blade portion 24 which extends forwardly from the handle portion 20, and which 45 has a transversely flat nether surface 26 similar to the upper surface of the member A. Cross-sectionally the blade 24 is similarly shaped with relation to the blade 12 for most of its length and has a vertical right hand sharpened shearing edge 28, looking from the rear, 50 adapted to slidably pass the cutting edge 16 of the blade 12 in shearing action, ending forwardly in a dull non-cutting edge 29 adjacent its end 32.

The two members A and B are pivotally connected 55 intermediate their ends by a screw or pin 30, the connection being sufficiently loose to permit slight vertical play between the two members.

The extreme forward end 32 of the top member A is formed into a sharpened tip or point ending just short of the blunt point 14 of the bottom member.

60 The finger grips 8 and 22 lie in substantially the same plane and meet as at 34 when the members are pivoted to bring the blade portions together in closed over-lapping relation. Longitudinally the blade portion 24 is arcuately curved upwardly, as is best illustrated in Fig. 2, allowing 65 the shearing edges 16 and 28 to slidably pass each other in a single point shearing contact action as the blades are pivoted into closed position. When the blades are closed, as illustrated in Fig. 2, a small space 36 separates the two intermediate the pivot pin 30 and the non-cutting tip ends 14 and 32. When the blades are in closed position the non-cutting tip portions 14 and 32 lie in substantial face 70 to face over-lapping contacting relation. As is best illus-

to

trated in Fig. 3, when the blades are in closed position the two points 14 and 32 do not lie in actual vertical alignment, the point 32 residing slightly to the left of the blunt point 14 to form an elongated substantially V-shaped opening 38 between the two points. As seen in Fig. 2, the two points 14 and 32 are slightly bent arcuately in an upward direction.

The upper surface of the blade portion 24 has a boss 40 adjacent the sharp point 32, the upper surface of which is cupped or recessed and knurled, as at 42, to nest the ball of a person's thumb, whereby the upper blade 24 may be swung laterally with relation to the bottom blade 12.

The outer or lower surface of the bottom blade is provided with a similar recess 43 (Fig. 5) for nesting the tip or forward portion of a person's finger in co-operation with the thumb, as more fully explained hereinbelow. The surface of the recess 43 is preferably knurled, not shown, to prevent slippage of the finger with relation to the blade 12.

Operation

In utilizing the device for drawing seam threads from cloth, the tool is grasped in the right hand in such a manner that the recess 43 of the bottom blade 12 is grasped by the first finger at any point between the tip and the second joint of the forefinger, with the upper surfaces of the blade portions being grasped by the little finger, and with the ball of the thumb nested in the recess 42 of the boss 40. In this position the other fingers naturally fall over the central portion of the upper member B. Movement of the thumb toward the left hand will act to open the points 14 and 32 laterally. In starting the thread pulling operation the point 32 is thrust under one of the loops 44 of the seam thread in order to draw it upwardly from the upper surface of the cloth 46 in which it is sewed. The upward curve of the point 32 facilitates its insertion into the loop. The points 14 and 32 are then swung together, and since the vertical edges 18 and 29 are dull, and since the pivotal connection between the two members allows slight vertical play the thread is not severed, but instead, it will be forced to extend flatly between the upper surface of the tip 14 and the bottom surface of the point 32. This is best illustrated in Fig. 4, wherein the thread is indicated by the numeral 48. Downward pressure of the thumb acts to flatten the thread and thus weaken it at this point and hold the same tightly impinged between the two blade points. A quick upward jerk or pull on the thread acts to pull one or more of the loops 44 from the cloth before the thread is broken. The thread will break at its weakened point between the tips 14 and 32, thus leaving a length of the thread projecting above the cloth which is then again grasped by the tips adjacent the surface of the cloth. If the thread should break adjacent the cloth the starting operation, as disclosed above, is repeated.

When it is desired to use the tool for cutting the thread or the cloth, the handle grips 8 and 22 are grasped by the fingers and the tool used in a manner conventional with scissors.

Obviously the invention is susceptible to some change or alteration without defeating its practicability, and I therefore do not wish to be confined to the preferred embodiment shown in the drawings and described herein,

further than I am limited by the scope of the appended claims.

I claim:

1. A thread pulling tool, including: a pair of elongated members pivotally connected loosely intermediate their ends in overlapping relation forming a pair of blades on one side of said pivotal connection, said blades having adjacent flat complementary faces slidably disposed in overlapping relation ending in blunt-edged substantially overlapping non-cutting free tip-end portions remote from said pivotal connection; means for moving the non-cutting tip end portions toward and away from each other, said means including a boss on the outwardly disposed surface adjacent the free end of one said blade, said boss having a concave recess in its surface, a concave indentation in the surface of the other said blade oppositely disposed with relation to the recess, said recess and said indentation being dish-shaped and adapted to complementally receive, respectively, the ball of the thumb and tip of the first finger of the operator; a sharpened point of the free end of said blade projecting beyond said boss; and a blunt tip on the free end of the other said blade and projecting beyond said sharpened point.
2. A thread ripping tool, including: a pair of elongated members pivotally loosely connected intermediate their ends in overlapping relation forming a pair of blades on one side of said pivotal connection and a pair of handles on the other side of said pivotal connection, said blades having adjacent flat complementary faces slidably disposed in overlapping relation and ending in blunt substantially overlapping non-cutting free tip-end portions remote from said pivotal connection for impinging a thread therebetween, said handles having blunt parallel proximal abutting faces for limiting the overlapping closing action of said blades; means for moving the non-cutting tip end portions toward and away from each other, said means including a boss on the outwardly disposed surface adjacent the free end of one said blade, said boss having a concave recess in its surface, a concave indentation in the surface of the other said blade, said indentation being oppositely disposed with relation to the recess in said boss, said recess and said indentation being dish-shaped and adapted to complementally receive, respectively, the ball of the thumb and the tip of the first finger of the operator; a sharpened point on the end of that blade extending beyond said boss; and a blunt tip on the free end of the other said blade and projecting outwardly beyond said sharpened point.
3. Structure as specified in claim 2, in which said recess and said indentation have knurled surfaces adapted to prevent slippage of the user's thumb and finger with relation thereto.
4. Structure as specified in claim 2, in which said sharpened point and said blunt end are co-operatingly arcuately curved toward said boss.
